DESIGN FOR A DISPLAY PLACARD OR THE LIKE

Arthur O. Schilling, Rochester, N. Y., assignor to
The Seventh Worlds Poultry Congress and Exposition, Cleveland, Ohio

Application April 14, 1939, Serial No. 84,294

Term of patent 3½ years

To all whom it may concern:

Be it known that I, Arthur O. Schilling, a citizen of the United States, residing at Irondequoit, Rochester, in the county of Monroe, State of New York, have invented a new, original, and ornamental Design for a Display Placard or the like, of which the following is a specification, reference being had to the accompanying drawing, forming a part thereof.

The figure is a plan view of a display placard or the like showing my new design. The article is of no appreciable thickness and all parts thereof are flush with the surface.

I claim:

The ornamental design for a display placard or the like, as shown and described.

ARTHUR O. SCHILLING.
